GEORGE STARR WHITE, OF LOS ANGELES, CALIFORNIA.

THERAPEUTIC DEVICE.

Application filed July 30, 1923. Serial No. 654,654.

This invention relates to therapeutic devices, and particularly to that type of therapeutic device which may be utilized for the purpose of controlling other devices as to periodicity.

In one application of my device the same may be utilized for treating disease by means of light, and particularly colored light.

10 The invention has for an object the provision of means for regulating the modality of rhythmic stimulation.

With the above and other objects in view, the invention consists in the novel and useful provision, formation, construction, association and relative arrangement of parts, members and features, as well as a method of use of the said device, all as shown in one embodiment in the accompanying drawings, 20 described generally, and finally pointed out in claims.

In the drawings:

Figure 1 is a fragmentary top plan view of the therapeutic control device;

25 Figure 2 is a fragmentary side elevation of the device shown in Figure 1;

Figure 3 is a fragmentary end elevation of the therapeutic control device shown in Figs. 1 and 2;

30 Figure 4 is a diagrammatic view of the wiring connections for the device illustrated in Figs. 1 to 3 inclusive;

Figure 5 is a fragmentary vertical sectional view, on an enlarged scale, of certain 35 features of the device;

Figure 6 is a fragmentary cross sectional view on an enlarged scale, of a clutch mechanism for said device;

40 Figure 7 is a fragmentary longitudinal sectional view on an enlarged scale, of features of the device and taken on the line 7—7 of Figure 1;

45 Figures 8 and 9 are perspective views of certain members used in the said device for regulating the periodicity of means associated therewith.

Figure 10 exhibits the external controls.

Corresponding parts in all the figures are designated by the same reference characters.

50 Referring with particularity to the drawings, the improved device is designated as an entirety by A, and said device as an entirety is so constructed with its parts interrelated as to provide for a change of modality in the treatment of disease. The improved device A is particularly formed to

control the periodicity of other devices used in therapeutic treatment or, in fact, in any device, whether therapeutic or not, in which some positive means of control is necessary. 60

To house the mechanism of the device A, a casing a may be provided, and said casing a has its interior devisioned so as to segregate various parts of the apparatus and to give the apparatus a pleasing appearance to 65 the eye. The casing includes the usual side walls 1 and 2, end walls 3 and 4, with two partitions within the same, as 5 and 6, there likewise being provided the usual top and base members 7 and 8. A housing b for certain parts of the device A is carried upon a sub-base 9 immediately above the base member 8. The device includes several working parts so inter-related as to accomplish the function required of the device, and said 70 parts include means c for controlling the periodicity of the devices to be associated with the complete device A, means d for regulating and actuating the means c, means e for controlling the means d, means f for 75 controlling the means d and in turn the means c, and means g directly co-operating with the means c and controlling certain parts of said means c, all of which means as just set forth combine in practicing one embodiment of the invention.

To get a clear understanding of the invention, the various means will be briefly summarized to show the relation that exists between them and the particularity thereof 80 as the description proceeds.

The means c includes a series of stationary and movable segmental members, there being a series of switch arms mounted upon a shaft adapted to be rotated through the medium 95 of the means d just described. The movable segmental members operate in conjunction with the stationary segmental members and it is thus possible, by regulating the movable segmental members, to increase the length of 100 the path over which the switch arms pass. Thus, if we provide suitable electrical connections with the fixed segments and with the switch arms and lead certain of said electrical connections to other devices, as, for 105 instance, a blue colored lamp and a red colored lamp, it is possible to regulate the burning period or the illuminating period of either one of the lamps, dependent upon the speed with which the shaft carrying the 110 switch arms rotates, and likewise the relative adjustment of the movable segments to the

fixed segments. The speed of rotation of the shaft upon which the switch arms are mounted is in measure regulated by the means *f* which controls the means *d*, and the relative adjustment of the movable segmental members with relation to the fixed segments is controlled by the means *g*.

The means *c* is best illustrated in Figures 5 and 7, with certain parts thereof illustrated in Figures 8 and 9. *h* designates the movable segment member, *j* the fixed segment member, and *k* one of the switch arm members. Included within the means *c* are two cages, generally indicated 10 and 11, spacedly mounted upon the sub-base 9. The said cages include spaced upright walls or brackets, 12 and 13 for the cage 10, and 14 and 15 for the cage 11, and the upright 14 of the cage 11 is formed with a journalled opening 16, and the cage 10 has both of its upright members 12 and 13 formed with journalled openings 17 and 18. The member *h* includes two brackets, 19 and 20, held in spaced relation by blocks 21 and 22, with the bracket 19 provided with a stud shaft 23 having a bearing portion therein, as shown at 24, and adapted to be carried in the journal opening 16 of the cage 11, and within the bearing opening 24 of the stud shaft 23 is a shaft 25. The stud shaft 23 is carried in the journalled openings 17 and 18 of the cage 10. Carried upon the shaft 25 and within the cage 11 is a gear 26, and associated with the stud shaft 23 and carried thereby and within the cage 10 is a gear 27. A sleeve shaft 28 of insulation material is carried upon the shaft 25, being keyed or otherwise held to said shaft 25, and the sleeve shaft 28 is interposed between the brackets 19 and 20 of the member *h*. Carried upon the periphery of the sleeve shaft 28 are two spaced annular members 29 and 30, the said last named members being termed contact rings, in that they are formed of some electricity conducting material. The member *j* includes two spaced bracket members 31 and 32, between which extend blocks 33 and 34. The brackets 31 and 32 are carried by the walls 13 and 14 of the cages 10 and 11, respectively. Joined with one of the blocks 33 or 34, that in the showing being the block 34, are finger members 35 and 36, and said fingers are each curved near one tip for frictional engagement with rings 29 and 30, as shown at 37 and 38. Carried by the blocks 33 and 34 are segments 39 and 40, the said segments being held to their respective blocks by any suitable means, such as bolts 41, passed through openings in the segment and the block and held in assembled relation by means of nuts 42 upon said bolts. In this connection, the blocks may be slightly arcuated to accommodate for the curvature of the segments.

65 The member *j* is so located that the segments

39 and 40 thereof would lie in a curved plane generated by swinging an arc from the center of the shaft 25. The member *h* has mounted upon its respective blocks 21 and 22 segmental members 43 and 44, and said segmental members are adapted to contact with and operate in conjunction with the segmental members of the member *j*. Referring to Figure 5, it will be seen that the member *h* is so mounted with respect to the shaft 25 that it lies in the same curved surface as the segments 39 and 40, assuming a curved surface having a radius equal to the distance between the center of the shaft 25 and the inner surface of the end of the segments. This of course is only approximately true, for the reason that the segments 39 and 44 are adapted to co-operate and to be in frictional engagement with one another, which fact is likewise true for the segments 40 and 43, as inspection of Figure 5 will show. In fact, the segments 43 and 44, where they co-operate with the segments 40 and 39 respectively, have a washout or tapered construction, as shown at 45. A series of spacedly fixed and movable segments may be provided, as illustrated in Figure 7 at 46, 47, 48 and 49, depending upon the device or number of devices to be controlled by the device A. As before, the blocks 21 and 22 upon which the segments 43 and 44 are mounted are provided with a concave face so as to accommodate the curve of their respective segments, and the said segments, as in the case of the member *j*, are provided with means 41 and 42 for inter-connecting the segments to the blocks. Adapted to play over said segments, or portions or areas of said segments, both fixed and movable, is the switch member *k*, it being understood that one switch as an entirety *k* is provided for each complete set of fixed and movable segments, that is, there would be one complete switch member *k* for each complete set of segments illustrated at the points 46 to 49 inclusive. The switch member *k* is detailed in Figure 9, wherein it will be seen that the same comprises a half ring bracket 50, the ring portion 51 thereof carrying a furcated stud 51^a, and within the furcation of said stud and pivoted at some point between its extremities by a suitable pin 52, is a switch arm 53, said switch arm 53 carrying a brush 54 secured to one extremity 55 of said arm by any suitable means. Between the opposite extremity 56 of the switch arm and leg 57 of the half ring bracket 50 is a contractile member 58. The switch members *k* are mounted upon the contact rings either 29 or 30. In the showing of Figure 7 two of the members *k* are spacedly mounted upon the ring 29 and two more members *k* are spacedly mounted upon the ring 30. In this connection, the curved part 51 of the

half ring bracket is joined to its respective ring, 29 or 30 or both, by any suitable securing means, as 59 (see Figure 5). Referring to Figure 5, it will be seen that the brush 54 is at all times urged against the segmental members through the medium of the contractile member 58 exerting a downward pull upon the extremity 56 of the switch arm 53.

The means *g* for regulating movement of the movable segments of the means *c* includes a shaft 60 carrying at one end a journalled bushing 61 associated with the wall 5, the opposite end of said shaft being carried in a journalled portion of the cage 10. The shaft 60, carries a worm 62 within the cage 10, which worm engages the gear 27. Keyed to the shaft 60 is a sprocket wheel 63, and a second shaft 64 extends through aligned openings in the walls 3 and 5, one end of said shaft 64 carrying a knob 65 and the opposite end carrying a small sprocket wheel 66. Over said sprockets 66 and 63 is passed a continuous chain 67. Thus by turning the knob 65 the shaft 60 will be rotated through the medium of the chain 67, and this rotation of the shaft will rotate the worm 62, in turn moving the gear 27, which will move the member *h* and consequently move the segments carried thereby relative to the segments carried by the member *j*. Movement of the segments either to the right or left is regulated in a measure by a bell-crank arm 68, there being stop pins 69 and 70 carried by the cage 10 with which said bell-crank arms are adapted to contact in certain movement thereof. This will insure that one movable segment will never completely leave the extremity of one of the fixed segments, consequent upon movement of the control 65 as shown in Figure 10, which represents an end view of the device A. The knob *g* is entitled the "periodic control" knob. Adjustment of the movable segments may be accurately ascertained as to whether the segment 43 shall rest entirely upon and over the segment 40, with the segments 44 and 39 co-operating to form a long path over which the brush 54 is passed, this being indicated by means of a pointer 71 mounted upon a short shaft 72 passed through the end wall 3 and carrying a gear 73, which gear meshes with an idler 74, with the idler in turn meshing with a gear 75 carried on the shaft 64. The graduations over which the pointer passes are marked "Left" and "Right", depending upon movement of the member *h* to the left or right, and the numbers of said graduations are arbitrary and might designate centimeters, inches and fractions thereof, or any other designation that might be desired. In other words, if the pointer rested at "7" as shown in Figure 10, the movable member *h* and the member *j* would be sub-

stantially in the relation shown in Figure 5, which is to say that the length of travel of the switch member over the segments 39 and 44 would be the same as its length of travel over the segments 40 and 43.

The means for rotating the shaft 25 and in turn moving the switch arm *k* includes the means *d*, *e* and *f*. A stud shaft 76 is carried within the cage 11 and upon said shaft is mounted a double gear wheel 77, certain teeth of which mesh with the gear 26 and other teeth of which are in mesh with a worm wheel 78 carried upon shaft 79. The said shaft 79 is suitably supported in journalled bearings in the cage 11, as shown at 80 and 81, and said shaft 79 likewise carries a wheel 82 keyed to said shaft 79 so as to permit longitudinal movement of said wheel thereon. The wheel 82 is associated with a member 83, which member likewise has a journalled portion through which the shaft 79 may be passed. A motor 84 has the usual shaft 85 and carried at one end of said shaft is a disk 86. The face of the disk 86 may be moved so as to engage the tread 87 of the wheel 82. The rear face of the disk 86 carries a series of vanes 88 with a hood or guard 89 passed over said vanes so that when the motor is running a draft will be created for the purpose of cooling the working parts of the motor. It is obvious that the distance from the center of the disk 86 to the point of contact of the tread 87 of the wheel 82 will determine the rotative speed of the wheel 82 and consequently the rotative speed of the shaft 79, and in turn the rotative speed of the switch members *k*. Thus, by suitable adjustment by the means *f*, it is possible to regulate the rotative speed of the switch arms *k*, dependent upon adjustment of the wheel 82 with relation to the disk 86. The means *f* includes a shaft 90 passed through the walls 3 and 5, one end of said shaft carrying a knob 91 and the opposite end thereof being coupled through a suitable coupling 92 with a worm shaft 93. A screw threaded block 94 is adapted to have a screw threaded engagement with the worm shaft 93, and the said screw threaded block 94 is carried by suitable extensions 95 associated with the member 83. To determine the relative position of the wheel 82 with respect to the disk 86, I may provide an indicating dial 96, the movable pointer of which, 97, is mounted upon a stud shaft 98 passed through the wall 3 with an end of said shaft carrying a gear 99 in mesh with an idler 100, which idler in turn meshes with a gear 101 upon the shaft 90.

The means *e* is in reality a clutch, and the said means functions to move the shaft 85 of the motor 84 and consequently move the disk 86 into engagement with the wheel 82 or out of engagement with said wheel. The

motor carries two spaced lugs, 102 and 103, carrying cross pieces 104 and 105. The cross piece 104 is formed to carry a shaft bushing 106, there being a stud shaft 107 carried 5 within said bushing 106, as shown at 108, with an end of said stud shaft, as 109, formed with a key or tongue 110 for reception within a transverse groove 111 in an end of the motor shaft 85, all as illustrated in Figure 10 6. Likewise carried by the bushing 106 is a collar 112 and between said collar and the member 105 and surrounding the stud shaft 107 is an expansible member 113. The member 112 carries two pins, as 114 and 15 115, and the said pins are adapted to be acted upon by members 116 and 117, the said members being interconnected by means of a cross piece 118, which cross piece in turn is mounted upon a shaft 119, which shaft 20 in turn is joined with a shaft 120 through the medium of a suitable adjustable coupling 121 with the said shaft 120 passed through a journalled opening in a bracket member 122, the said bracket member in 25 turn being mounted upon the sub-base 9 of the device A. The shaft 120 carries a part 123 with which a cam 124 may engage, the said cam in turn being mounted upon a shaft 125 with the shaft adjacent to the cam 30 suitably journalled within a bracket 126. Interposed between the top 127 of the bracket member 122 and the member 123 is an expansible member 128. The shaft 125 in turn is coupled with a shaft 129 passed 35 through the walls 3 and 5, there being a knob 130 carried on said shaft at an end thereof with the shafts 129 and 125 suitably connected by a coupling 131. A torsion spring 132 is mounted in connection with 40 the end 5 and the shaft 129. Thus, upon rotating the knob 130 the shaft 125 will be rotated, which in turn will rotate the cam 124, the said cam having its periphery so shaped as to raise or lower the shaft 120, 45 which in turn will raise or lower the shaft 119 and the members 116 and 117 associated with the part 118 connected to said shaft 119. The members 116 and 117 are provided with cam faces 133 and 134, which 50 cam faces are adapted to engage with the pins 114 and 115 when the cam is in a raised position, substantially as shown in Figure 3, for the purpose of forcing the shaft 85 inwardly and causing the disk 86 to engage 55 with the tread 87 of the wheel 82. To properly lubricate the various parts at the journalled portions, I provide oil cups 135, which oil cups may be conventional in form with a tube 136 leading therefrom directly to the 60 bearing, similar to that shown in Figure 6. In Figure 6 it will be noted that on said shaft 107 is mounted a bearing collar 137 and the member 105 is provided with a ball-race 138 and has between said collar 137 65 and the member 138 ball bearing members

139, with the tube 136 leading directly to said bearing members. A similar construction may be provided at the other points for the various shafts, or in fact any place where a rotating part is journalled. 70

In order to make a quick break between the segments 43 and 44; and 39 and 40 as the switch arm or switch arms *k* revolve, one movable segment, as 44, and one fixed segment, as 40, have one end flared as shown 75 at 140 and 141. Thus, as the brush of the switch arm leaves the movable segment 43 it immediately snaps onto the flared portion 140 and then commences its movement over the member 44. The same is true for the 80 part 141. This makes a quick break and a break without arcing.

Referring now particularly to Figure 4, wherein the wiring circuits of this device are 85 diagrammatically set forth, 142 and 143 are the leads from some source of electric current supply, and from said leads we have circuits 144 and 145. The circuits 144 and 145 are associated with independent contact plugs 146 and 147. Each contact plug 146 and 147 is directly associated with a double throw switch *m*, the contact plug 146 being connected through suitable leads 148 to two poles 149 of the switch *m*, and the contact plug 147 through leads 150 being likewise associated with two poles 151 of the switch *m*. The two contact arms 152 and 153 of said switch are associated with the motor 84 and with a series switch 154 through leads 155. It will be noted that the two contact arms are only connected through the medium of the switch 154. Included in the circuit 148 and the circuit 150 are switches *n* and *o*, each lead of said mentioned circuits 148 and 150 leading to a terminal of 100 their respective switch members, the said switch members being each of the two-pole type provided with two switch arms. From the arms of the switch *n* are leads 156, 157 and 158, and from the arms of the switch *o* are leads 159, 160 and 161. The lead 158 leads to the brush 36 of the member *c* and the lead 161 leads to the brush 35 of the member *c*. The lead 157 is directly associated with one pole of the one-way switches *p* and *q*, and the lead 156 is associated with one pole of the two plugs *r* and *s*, and from the second pole of each plug *r* and *s* there are leads 162 and 163 associated with the second pole of the switches *p* and *q*, there being binding posts 164 and 165 at said points of association. From the posts 164 and 165 are connected leads 166 and 167, both leads leading to independent contacts 168 and 169 of a switch *t*. The said switch arms 168 and 169 of the switch *t* in the position shown in 115 Figure 4 will rest upon contact points associated with leads 170 and 171, the said leads 170 and 171 in turn communicating with independent segments 40 and 43 at 130

the points marked 46 and 47, Figure 7. If the switch were thrown into a second position so as not to rest on the contact points associated with the leads 170 and 171, the 5 switch arms would then contact with contact points associated with leads 172 and 173 associated with the independent segments 39 and 44, in the position of 46 and 47 of Figure 7. The lead 159 is directly associated 10 with one terminal each of the two plugs *u* and *v*, the second terminal of said plugs being associated through suitable leads 174 and 175 with one terminal of the single throw switch members *w* and *y*, the said 15 leads 174 and 175 being associated with said switch members through suitable posts 176 and 177, and from said posts are connected leads 178 and 179 in turn connected to the independent segments 40 and 43 at the points 20 48 and 49, see Figure 7. It will be noted that the device *c* is in Figure 4 carrying the switch arms *k* mounted upon the parts 29 and 30 of said member *c* considered as an 25 entirety. To illustrate the invention in more detail I have associated with the plug *u*, that is, by plugging in on the circuit the lamp member *z*, and with the plug *r* the lamp member *zz*. We will assume that the lamp member *z* is blue and the lamp member *zz* is red. Upon throwing the switch *m* 30 into the position substantially as illustrated in Figure 4, and in turn throwing the switch 154, will start the motor rotating, and by throwing the switch *n* so that its two contact arms will contact with their respective contact points, the circuit will be completed to the plug *r*, through the light *zz*, and thence to the arm 169 of the switch *t*. Through 35 said arm the circuit will go to the segments 40 and 43 in the position marked 46 and 47 of Figure 7, and current will be led through the lead 158 to the brush 35, which in turn permits electrical circuit through the switch arms *k*. As far as the opposite side 40 is concerned, the current will at all times be led to the segments 40 and 43, located at points 48 and 49 of Figure 7. Now if the shaft of member *c* were turned, and assuming the parts in the position shown, the red light and the blue light would come on at the same time, hence if the switch *t* were thrown so that the arms 168 and 169 were in contact with the contact points associated with the leads 172 and 173 the circuits would 45 be completed to the segments 40 and 43 at the points 48 and 49 and there would be an alternation of the lights as the switch arms *k* swung over the segments. In other words, the red light *zz* would be on for a 50 definite time and then the blue light *z* would burn, the red light being extinguished. If it is desired to regulate the periodicity, the movable segments would be rotated relative to the fixed segments so that the switch arm 55 or switch arms would have a longer path to traverse over certain of said segments and thus one or the other of said lights would burn a longer period of time. It will follow that any time period or duration of light 70 period may be obtained as the speed of rotation of the motor may be varied if desired, although means for varying the speed of rotation of the motor are not shown. What is shown is a transmission mechanism, that is, the means *d*, and the adjustability 75 of the movable segments relative to the fixed segments. Numerous sets of lights may be associated with the plugs *r*, *s*, *u* and *v*, and if the switches *p*, *q* or *w*, *y* are thrown into position the lamp or lamps will burn steadily. In other words, it is possible to have certain of said lamps burning steadily, irrespective of movement of the switch arms *k* over the segments, or if two lamps *zz* were 80 associated with the plugs *r* and *s* and only one lamp *z* with the plug *u*, the switch *m* might be thrown into position so as to contact with the points 151 and thus reduce the load on one side of the current supply. In 85 the diagram of Figure 4 it will be noted that the segments 39 and 44, at the points marked 48 and 49 in Figure 7, are not shown inasmuch as they are disconnected and have no wiring circuits leading thereto, although it is obvious that they might have. In the 90 showing, we might plug in a third light on the plugs and throw the switch *q* into operative position. This third light would then burn steadily, while the blue and the red lights would alternate as to light and shade. 95 It will thus follow that any combination of lights or color in their periodicity or burning periods may be provided for. 100

It is obvious that various changes, modifications and variations may be made in 105 practicing the invention in departure from the particular showing of the drawings, and the method of application of the said device as to modality, and that said variations may be made within a fair interpretation of the 110 invention as set forth by the scope of the appended claims.

Having thus disclosed my invention, I claim and desire to secure by Letters Patent:

1. A device of the character disclosed 115 adapted to control the illumination of two lamp members, including four segmental members arranged in spaced cooperating pairs, a switch member for play upon such segmental members, such segmental members being adjustable as to the length of path to be traversed by such switch member, whereby selected periodicity of the illumination of each respective lamp may be regulated. 120

2. A therapeutic device of the character disclosed, adapted to control the periodicity of devices, comprising a switch member, a member for contact with said switch member, and means for varying the duration of control of said switch member with the con- 125

130

tact member; said means including a member variably controlling movement of said switch member, and means for varying the length of the member for contact with said switch member.

3. A therapeutic device adapted to regulate the burning of lamps, including means for effecting a burning of such lamps, and means for controlling the current load on 10 said first named means.

4. A therapeutic device adapted to regulate the burning of lamps, including means for effecting a burning of such lamps, and means for controlling the current load on said first named means; further means being 15 provided for controlling current load to such lamps.

In testimony whereof, I have signed my name to this specification.

GEORGE STARR WHITE.
